UNITED STATES PATENT OFFICE.

JOHN BERG, OF CHICAGO, ILLINOIS, ASSIGNOR TO METAL SPECIALTIES MANUFACTURING COMPANY, OF CHICAGO, ILLINOIS, A CORPORATION OF ILLINOIS.

ELECTRICAL DEVICE.

Application filed April 21, 1923. Serial No. 633,799.

My invention, as to one phase thereof, relates to a structure involving a reel, and the wire thereon, which is connected with an element to be energized by the current and 5 may be unwound therefrom against spring resistance which operates to automatically re-wind the wire on the reel; another phase of my invention relates to a jack controlling the current to an element to be energized; 10 and another phase of the invention relates to the ignition device of an electric cigar lighter.

My primary objects are to provide a novel, simple and economical construction of electric reel which may be readily secured to an instrument board of an automobile, at an aperture therein, and when so positioned the reel proper of the device will extend at the rear side of the instrument board; to provide 20 a construction more particularly involving an electric reel, wherein the device to be energized, and which may be a cigar-lighting device, is connected with a jack controlling the flow of current to the device to be energized; 25 and the current through the jack is automatically arrested when the device is not in use, and the circuit automatically re-established through the jack upon moving the device to be energized, out of normal position; 30 and provide an electric cigar-lighter wherein danger of the burning of the hand of the operator handling the ignition device is prevented.

Inasmuch as I have devised my invention for embodiment more particularly in an electric cigar-lighter, I have chosen to so illustrate it in the drawings, in which:

Figure 1 is a view in side elevation of an electric cigar-lighter embodying my invention, portions thereof being broken away to disclose interior details, the device being shown as secured in position at the apertured portion of an instrument board of an automobile. Figure 2 is a front view of the 40 ignition element of the device. Figure 3 is a view like Fig. 1 showing the ignition element of the device withdrawn from the tubular member in which it is normally supported, the current-conducting wires connected therewith being partially unwound from the reel. Figure 4 is a view in longitudinal sectional elevation of a jack forming a part of the structure shown in Figs. 1 and 3, the section being taken at the line 45 4 on Fig. 6 and viewed in the direction of

the arrow. Figure 5 is a section taken at the line 5 on Fig. 2 and viewed in the direction of the arrow. Figure 6 is a plan view of the structure shown in Fig. 4, with the casing of the jack shown in section; and 60 Figure 7, a section taken at the line 7 on Fig. 4 and viewed in the direction of the arrow.

The particular illustrated embodiment of my invention comprises a spring reel device upon which the current-conducting wires 65 8 are wound, this device, which is represented generally at 9, being of any suitable construction, as, for example, of the construction shown in United States Patent No. 1,260,626, granted to me on March 26, 1918, 70 the shaft of the reel being represented at 10 and the re-winding spring at 11. The shaft 10 is supported at its opposite ends in the opposed side walls 12 of a housing 13 in which the operative parts of the reel, together with the wire wound thereon, are located, the peripheral wall of the housing 13 containing an opening 14 through which the outer end of the wire, on the reel, extends. The construction shown is adapted 75 to be secured in an aperture of an instrument board, as, for example, the instrument board of an automobile, such a board being represented at 15 with its aperture shown at 16, the device to this end being formed 80 of a tube 17 adapted to be inserted through the opening 16 in the instrument board and carrying nuts 18 and 19 threaded thereon and adapted to clamp the tube 17 in position 85 on the board, upon securing them tightly 90 against the rear and front faces, respectively, of the board 15. The nut 19 is preferably provided at its outer end with an internal annular shoulder 19^a against which the outer end of the tube 17 extends, the wall of the 95 opening through this shoulder part being rounded as shown at 19^b whereby the device is free of sharp or rough surfaces against which the wire bears in winding and unwinding it from the reel. The rear end of 100 the tube 17 is connected with the cross-piece 20 of a yoke-shaped bracket 21 which latter straddles the housing 13 and is secured against the side walls thereof, as by a screw 105 22 bridging the arms of the bracket, these arms preferably containing inwardly struck bosses 22^a which extend into recesses (not shown) in the side-walls of the housing and prevent turning of the housing on the bracket. The cross-piece 20 is apertured, as repre- 110

sented at 28, and the tube 17 is secured to this member at said aperture. A desirable way of securing these parts together, is to form the tube 17 with an upset portion 24 to form a flange between which and the offset portion 25, at the rear extremity of the tube 17, the yoke bracket is securely held to the tube.

The device shown also comprises a jack, 10 represented at 26, which is connected with the outer ends of the wires 8, which latter extend through the tubular member 17, this jack serving to control the flow of current to the ignition device hereinafter referred 15 to. The jack shown comprises a casing, or shell, 27 preferably constructed of any suitable non-heat-conducting material, the end wall of which is apertured, as represented at 28, through which aperture the wires 8 20 lead into the interior of the shell, the opposite end of the shell 27 containing a threaded electrical socket 29 the outer threaded contact of which is represented at 30 and the center contact of which is represented at 31. One of the wires 8 connects through 25 a strip 32 of current-conducting material, with the outer contact 30, the strip 32 being held in position by a screw 33 passing through the casing 27 and screwing into 30 this strip, and the other of the wires 8 connects with a spring contact strip 34 supported at one end by, but out of electrical contact with, the contact strip 32, through 35 the medium of a rivet 35. The free end of the strip 34 which extends directly above a resilient strip 36 of current-insulating material, likewise supported by the strip 32 at the rivets 35, cooperates with the contact portion 37 of the center contact 31, the parts 40 being so constructed and arranged that when the jack 26 is removed from the tubular member 17, in which it is located when the device is not in use, the contact strip 34 will 45 be in engagement with the contact portion 37 as shown in Fig. 4, whereby the circuit through the jack is closed. The means provided in the particular construction shown for automatically breaking the circuit through the jack when the latter is inserted 50 into the supporting tube 17, and causing the circuit to become re-established upon withdrawing the jack from the support, comprises a button 38 which is located, and longitudinally movable, in an opening 39 in a 55 side wall of the casing 27, the inner end of this button being connected with the contact 34. The parts are so proportioned that when the contact 34 is in engagement with the contact portion 37 the button 38 projects 60 laterally beyond the outer surface of the casing 27 and is forced inwardly to a position in which the contact 34 disengages from the contact portion 37, by the engagement of the button with the inner surface of the 65 tube 17, upon introducing it into the latter

to the position shown in Fig. 1, the contact 34 automatically engaging with the contact portion 37, upon the withdrawal of the jack from the tube 17. The jack 26 is adapted to receive any suitable device to be energized, 70 as, for example, the cigar-lighting element represented generally at 40 and illustrated in detail in Fig. 5. The particular igniting device shown comprises a metal shell 41 formed at one end with the reduced threaded portion 42 adapted to screw into the threaded contact 30 of the jack, the opposite end of this shell being open as represented. The shell 41 contains a body 43 of any suitable current-insulating material and the electrical heating element shown as in the form of a coil and represented at 44, one end of this coil being connected with the shell 41, as represented at 45, and the other end thereof, represented at 46, connected with a screw 47 which is insulated from the shell 41 by the interposed material 43, the contact 47 cooperating with the center contact 31 of the jack. The heating coil 44 is shown as interposed between disks 48, 49 and 50 preferably of mica and provided in accordance with common practice, the disks 49 and 50 containing registering openings therein permitting of access to the coil 44 for the lighting of a cigar. The device 40 also comprises a band 51 of heat-non-conducting material which surrounds the shell 41 and adapts the device to be handled by the operator without danger of burning his fingers. When the device 40 is assembled with the jack 26 these parts virtually form a unitary structure which is adapted to be withdrawn from the tube 17 to the desired point of use, the wires 8 unwinding from the reel 9 in this operation, it being understood that upon removing the jack 26, as stated, the circuit is immediately established through the jack.

It will be noted from the foregoing that inasmuch as the heating element 40 is surrounded by the member 51 of non-heat-conducting material, danger of the burning of the fingers of the operator, in grasping this part of the device, is prevented, it is not necessary that any more of the device than the part just referred to be exposed at the front side of the board 15, and thus the device is rendered very inconspicuous.

While I have illustrated and described a particular construction embodying my invention, I do not wish to be understood as intending to limit it thereto as the same may be variously modified and altered without departing from the spirit of my invention.

What I claim as new, and desire to secure by Letters Patent, is:

1. In a device of the character set forth, the combination of a frame, a spring-actuated reel mounted therein, a stationary tubular guide-member, a jack comprising a tubular jack-casing adapted to be sheathed in

said tubular guide-member and provided with a lateral perforation, a movable circuit-closer mounted in said jack-casing, a contact in said jack-casing automatically engaged by said circuit-closer when the jack-casing is withdrawn from the tubular guide-member, and a button projecting through the lateral perforation of the jack-casing and adapted to be actuated by said tubular 5 guide-member to break the circuit in the operation of sheathing the jack-casing, and an electric cord connected with said reel and serving to draw said jack into its sheathed position and cause the circuit to be automatically broken thereby.

2. In a device of the character set forth, the combination of a frame, a spring-actuated reel mounted therein, a fixedly mounted tubular guide-member upon which said 10 frame is mounted and carried, a jack comprising a tubular jack-casing adapted to be sheathed in said tubular guide-member and provided with a lateral perforation, terminals for said jack, a contact member connected with one of said terminals, and a circuit-closer mounted in said jack-casing and adapted to engage said contact, said circuit-closer having secured thereto a laterally projecting button extending freely 15 through said perforation, and an electric cord connected with said tubular guide-member, said cord being extended into and secured to said jack-casing and having one

conductor electrically connected with said circuit-closer and another conductor electrically connected with the other terminal of the jack, said circuit-closer serving to automatically close the circuit when the jack-casing is withdrawn from the guide-member and said button serving to engage 20 the tubular guide-member and automatically move the circuit-closer to the circuit breaking position when the jack is drawn into the tubular guide-member by the action of the reel and cord.

3. In a device of the character set forth, the combination of a tubular guide-member adapted to serve as a sheath for a jack, means for clampingly securing said member in a perforation in a support, said means including a nut screwed upon the front end of said member and having an internal flange abutting against the end of said tubular member, the wall of the opening through said nut being rounded and outwardly flaring, in combination with a jack comprising a tubular member adapted to be sheathed in said guide-member, and a circuit-closer in said second named tubular member equipped with a laterally projecting button adapted to be forced inwardly by the guide-member to automatically break the circuit in the operation of sheathing the jack in said 35 guide-member.

JOHN BERG.
